ADJUSTABLE SPEED MATERIAL HANDLING DEVICE

Paul F. McAdams, St. Joseph, Mich., assignor to Clark Equipment Company, a corporation of Michigan
Filed Dec. 24, 1964, Ser. No. 420,972
5 Claims. (Cl. 214—140)

This invention relates to fluid motors, and more specifically to piston and cylinder type fluid motors having interchangeable speed control means and which are especially suitable for use with material handling vehicles such as tractor shovels.

Ordinarily, a tractor shovel is provided with a bucket which is pivotally mounted at the forward ends of a pair of boom arms and is actuated between a loading or digging position and a carry position by means of one or more double-acting fluid motors which are connected directly to the bucket and connected to the tractor shovel body or the boom arms. In a material handling vehicle such as a tractor shovel the maximum force required to actuate the bucket is the force required to pivot the bucket with a full load from the loading or digging position to the carry position. Once the maximum force which is required to actuate a fully loaded bucket from the loading position to the carrying position is determined, then it is a simple matter to choose a fluid motor having a piston area which, after subtracting the cross-sectional area of the piston rod, will provide sufficient force for pivoting the bucket under normal operating conditions. Heretofore, a conventional double-acting piston and cylinder type fluid motor has been used in such applications, and so the side of the piston opposite that to which the piston rod is connected presents a greater effective cross-sectional area. As a result there is actually a greater force available for pivoting the bucket forwardly from the carrying position to a loading position than vice versa which, of course, is unnecessary. Thus, it is an object of my invention to provide a double-acting fluid motor which has a retracting force that is greater than its extending force.

Further, since in a conventional piston and cylinder type fluid motor a larger volume of pressurized fluid is required to move the piston so as to extend the piston rod than to move the piston so as to retract the piston rod, the piston moves more slowly than when the piston rod is being retracted, assuming that the fluid flow remains substantially constant. This is undesirable because in order to run such machine efficiently they should be operated as rapidly as can be done safely. As a consequence, it is another object of my invention to provide a fluid motor which has an extension speed that is greater than its retracting speed.

A further object of my invention is to provide an improved fluid motor for use as a bucket tilt motor.

Still a further object of my invention is to provide a double-acting fluid motor having readily interchangeable speed control means.

In carrying out my invention in a preferred embodiment thereof I provide a fluid motor having a cylinder with an open end and a closed end. A piston is slidably disposed in the cylinder and has a piston rod attached thereto which extends outwardly through the closed end of the cylinder. A removable cap is attached to the open end of the cylinder. A speed control rod is removably connected to the piston and slidably extends through the cap.

The above and other objects, features and advantages of my invention will become more readily apparent to persons skilled in the art when the following detailed description is taken in conjunction with the accompanying drawing wherein:

2

FIGURE 1 is a side elevation of a tractor shovel embodying my invention; and

FIGURE 2 is a longitudinal sectional view of a preferred embodiment of my invention.

5 Referring to FIG. 1, the reference numeral 10 denotes generally a tractor shovel which includes a body 12 supported by a pair of front drive wheels 14 and a pair of rear dirigible drive wheels 16, only one of each being shown. Body 12 includes an operator's station 18 and an engine compartment 20 within which the vehicle prime mover is located. Pivottally connected to body 12 on each side thereof at 22 is a pair of forwardly extending boom arms 24. Each boom arm 24 can be elevated by means of a single acting fluid motor 26 which is connected at one end to boom arm 24 at 28 and pivotally connected at 30 to a downwardly depending bracket 32 attached to body 12.

Pivottally connected to the forward ends of boom arms 24 at 34 is a bucket 36. Disposed on each side of body 20 12 and connected to bucket 36 at 38 and to body 12 at 40 is a pair of bucket tilt assemblies 42, only one of which is shown. Referring now also to FIG. 2, each assembly 42 includes a double-acting fluid motor 44 and tubular extension member 46. Fluid motors 44 are actuatable to 15 pivot bucket 36 between the loading or digging position shown in FIG. 1 and a carrying position in which the open front of bucket 36 is substantially horizontal. Also, boom arms 24 and assemblies 42 cooperate so that as boom arms 24 are raised to elevate bucket 36 the attitude of bucket 36 is maintained substantially unchanged, whereby spillage of any load from the bucket is minimized.

20 Each fluid motor 44 includes a cylinder 48 which is closed at one end by a cap 50. It will be appreciated, 35 of course, that cap 50 may be integral with or separate from cylinder 48. The other end of cylinder 48 is closed by a removable cap 52 which may be threadably connected to cylinder 48 or bolted to a flange 54 which forms a part of cylinder 48. Slidably disposed within cylinder 48 is a piston 56 which forms with cylinder 48 and caps 50 and 52 a pair of fluid chambers 58 and 60. Connected to piston 56 is a piston rod 62 which extends outwardly through cap 50 and attaches at the outer end thereof to bucket 36 at 38 as was explained hereinabove. 45 Also connected to piston 56 is a speed control rod 64 which extends outwardly through cap 52. As shown, piston rod 62 extends through piston 56 and has a threaded portion 66 which threadably engages a cooperating threaded portion 68 in the adjacent end of speed 50 control rod 64, whereby rods 62 and 64 are connected to piston 56. It will be appreciated that cap 52 and rod 64 form speed control means, an increase in the cross-sectional area of the rod causing an increase in the extension speed of the motor, which are readily interchangeable with other speed control means having a speed control rod of different cross-sectional area. Cylinder 48 55 also is provided with a pair of fluid supply ports 70 and 72 which are located adjacent caps 50 and 52, respectively.

It will be understood that various packings and other fluid seals are utilized in fluid motors 44, as required, although they have not been described in detail. Also, it will be understood that fluid supply ports 70 and 72 are connected to a source of pressurized fluid via suitable fluid circuitry which includes a control valve for directing pressurized fluid to either one or the other of the ports or neither of them.

Turning now to the operation of my invention, it will be assumed that it is embodied in the tractor shovel shown in FIG. 1 and that an operator desires to actuate the bucket 36 from the position shown in FIG. 1 to a carry position. Pressurized fluid is supplied to chambers 58 of

fluid motors 44 through supply ports 70 so that pistons 56 are moved toward the left as shown in FIG. 2 to approximately the position shown in FIG. 2. At this point the open face of bucket 36 is substantially horizontal. Now, by supplying fluid motors 26 with pressurized fluid the boom arms 24 may be raised in order to elevate bucket 36. As boom arms 24 are being elevated, assemblies 42 are cooperating with them through a parallelogram linkage arrangement to maintain the open front of bucket 36 substantially horizontal. The bucket may then be dumped from the elevated position. In order to dump the bucket the operator actuates the control valve for motors 44 to supply pressurized to chambers 60 through ports 72. As a result pistons 56 moves toward the right until the bucket is pivoted far enough to dump the load therefrom. Because rods 64 have a greater cross-sectional area than rods 62, the force available for dumping bucket 36 is less than the force available for rolling back the bucket from the loading or digging position to the carry position. However, the bucket 36 may be pivoted forwardly to dump much more rapidly than it is pivoted back to the carry position due to the fact that rods 64 cause the volume of chambers 60 to be less than the volume of chambers 58; thus for a given amount of pressurized fluid supplied from the vehicle's hydraulic system the pistons 58 will move faster to the right than to the left.

Although I have described and illustrated a preferred embodiment of my invention, it will be understood by those skilled in the art that modifications may be made in the structure, form and relative arrangement of parts without departing from the scope and spirit of my invention. Accordingly, it should be understood that I intend to cover by the appended claims all such modifications which fall within the scope of my invention.

I claim:

1. In a material handling vehicle, a boom arm pivotally connected to the vehicle, a bucket pivotally connected to one end of said boom arm, and a bucket tilt assembly connected to said bucket and the vehicle, said assembly including a double-acting piston and cylinder type fluid motor, a speed control rod connected to said piston and extending outwardly through one end of said motor and a tubular extension member connected to said one motor end and connected to the vehicle.

2. In a material handling vehicle; a boom arm pivotally connected to the vehicle; a bucket pivotally connected to one end of said boom arm; and bucket tilt means connected to said bucket and the vehicle, said means including a cylinder with an open end and a closed end, a piston slidably disposed in said cylinder, a piston rod connected to said piston and extending outwardly through said closed

end and pivotally connected to said bucket, fluid port means for communicating fluid to said cylinder at one side or the other of said piston, and interchangeable speed control means, said speed control means including a cap removably connected to said open end and a speed control rod removably connected to said piston and extending outwardly through said cap so that said speed control means may be interchanged readily with other speed control means having a speed control rod with a different cross-sectional area.

3. A combination as set forth in claim 2 wherein said bucket tilt means includes a tubular extension member fixed to said cylinder and pivotally connected to the vehicle so that said member encircles said speed control rod when said speed control rod is extended.

4. In a material handling vehicle, material engaging means, means for raising and lowering the said material engaging means, and means for moving the said material engaging means back and forth between at least two operative positions, the last-named means comprising a double-acting piston and cylinder type fluid motor and means for adjusting the speed of the said fluid motor for one direction of operation, the said fluid motor including a piston rod which is connected to the piston of the said fluid motor and extends from one end of the said fluid motor and the said means for adjusting the speed of the fluid motor including a speed control rod connected to the said piston and extending in the opposite direction from the said piston rod.

5. A material handling vehicle as specified in claim 4 in which the said fluid motor includes a tubular extension member secured thereto and encompassing the said speed control rod.
